[57] CLAIM

The ornamental design for a bin for storage rack, as shown and described.

DESCRIPTION

FIG. 1 is a perspective view of a bin for storage rack showing my new design.

FIG. 2 is a plan view thereof.

FIG. 3 is a front elevation thereof.

FIG. 4 is a rear elevation thereof.

FIG. 5 is an end elevation thereof.

FIG. 6 is an enlarged partial section on line 6—6 of FIG. 2.

FIG. 7 is an enlarged partial section on line 7—7 of FIG. 2.

FIG. 8 is an enlarged partial section on line 8—8 of FIG. 2.

The end opposite to that shown in FIG. 5 is a mirror image thereof.

FIG. I

FIG. 2
